CLAIM

The ornamental design for portion of a toner container, as shown and described.

DESCRIPTION

FIG. 1 is a front perspective view portion of a toner container showing our new design;

FIG. 2 is a rear perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a right side elevational view thereof;

FIG. 8 is a left side elevational view thereof;

FIG. 9 is a front perspective view thereof, showing an alternate position of use;

FIG. 10 is a rear perspective view thereof, showing an alternate position of use; and,

FIG. 11 is a front elevational view thereof, showing an alternate position of use.

The broken line showing of portions of the toner cartridge is for illustrational purposes only and forms no part of the claimed design.
